Primary Examiner — Jasmine Mlinarcik(74) Attorney, Agent, or Firm — Kenneth L. Tolar(57) CLAIM

I claim the ornamental design for a ponytail and bun cap, as shown and described.

DESCRIPTION

FIG. 1 is a front, perspective view of the ponytail and bun cap according to the present invention.

FIG. 2 is a rear, perspective view of the ponytail and bun cap.

FIG. 3 is a front view of the ponytail and bun cap.

FIG. 4 is a side view of the ponytail and bun cap.

FIG. 5 is a top, plan view of the ponytail and bun cap.

FIG. 6 is a rear view of the ponytail and bun cap.

FIG. 7 is a bottom, plan view of the ponytail and bun cap; and,

FIG. 8 is a rear, plan view of the ponytail and bun cap, depicting an alternate lacing pattern.

The broken lines depict claimed stitching.
